(57) CLAIM

The ornamental design for a lawn edging, as shown and described.

DESCRIPTION

FIG. 1 is a front top right perspective view of the lawn edging of the present invention;

FIG. 2 is a front view thereof;

FIG. 3 is a rear view thereof;

FIG. 4 is a left side view thereof;

FIG. 5 is a right side view thereof;

FIG. 6 is a bottom view thereof;

FIG. 7 is a top view thereof;

FIG. 8 is a rear top right perspective view thereof;

FIG. 9 is a rear bottom right perspective view thereof; and,

FIG. 10 is a front bottom left perspective view thereof.

The portions of the lawn edging illustrated in broken lines form no part of the claimed lawn edging design.
